To all whom it may concern:

Be it known that I, Cyril W. Leigh, a subject of the King of Great Britain and a resident of East Orange, county of Essex, and State of New Jersey, have invented a new, original, and ornamental Design for a Plate or Similar Article, of which the following is a specification, reference being had to the accompanying drawing, forming a part thereof.

The drawing is a top plan view of a plate showing my new design, a repeat unit of which is contained between the dotted lines. Said unit is repeated about the circumference of the plate

The design comprises a plate or similar article having a continuous circular scroll around the border of the plate enclosed by pairs of spaced concentric circles and a heavy lined concentric circle extending between the edge of the plate and the outer pair of circles, all as shown.

I claim:

The ornamental design for a plate or similar article, as shown and described.
